UNITED STATES PATENT OFFICE.

JAMES H. COFFMAN, OF COLUMBUS, OHIO.

DESIGN FOR A VENEER-PRESSING MEMBER.

SPECIFICATION forming part of Design No. 34,181, dated March 5, 1901.

Application filed February 9, 1901. Serial No. 46,748. Term of patent 14 years.

To all whom it may concern:

Be it known that I, JAMES H. COFFMAN, a citizen of the United States of America, residing at Columbus, in the county of Franklin and State of Ohio, have invented and produced a certain new, useful, and original Design for an Article of Manufacture—to wit, a Veneer-Pressing Member—of which the following is a specification, reference being had to the accompanying drawings, forming a part thereof.

In said drawings, Figure 1 is a side view of the veneer-pressing member embodying my design. Fig. 2 is a plan view of the same.

Fig. 3 is a longitudinal vertical section of the same, taken on line 3 3 in Fig. 2, these three views being deemed necessary for full illustration.

The leading and essential feature of my design for a veneer-pressing member consists in the peculiar surface formation of the upper portion of the same between the curved line 1 1 and the straight line 2 2, and the same may be described as follows: The line 1 1 is curved from side to side of the upper surface and from end to end throughout its length takes the form of an arc of a circle. Each side edge of the upper surface between the points 1 and 2 proceeds from 1 down and around to 5 on an irregular curve, from 5 to 4 on a very slight compound curve, and from 4 to 2 on a smaller irregular curve than from 1 to 5. In Fig. 3 the edge which is taken on line

3 3 in Fig. 2, it will be seen, proceeds from the point 6, which is the point where the line 3 3 intersects the line 1 1, to a point between the points 5 5 in an irregular curve. Section-lines running parallel with line 3 3, if taken at intervals between line 3 3 and either outer edge 1 5 4 2, would proceed from the line 1 1 to a line connecting points 5 5 on irregular curves, and the curve of each section-line would diminish as the lines neared either outer edge 1 5 4 2. The remainder of the surface from a straight line connecting points 5 5 to the line 2 2 is straight across from side to side.

The several minor features which go to form my design for a veneer-pressing member may be stated as follows: The top between the line 1 1 and the edge *a* is flat, as also is the top portion between the line 2 2 and edge *b*. The sides are parallel planes, as also are the ends, and the bottom is parallel to the two flat portions of the top and stands at right angles to the sides and ends.

Having thus described my design, what I claim is—

The design for a veneer-pressing member substantially as shown and described.

Signed by me at Pittsburg, Pennsylvania, this 17th day of November, A. D. 1900.

JAMES H. COFFMAN.
